ETER COMPANY, OF BOSTON, MASSACHUSETTS, A CORPORATION OF ARIZONA TERRI-
TORY.

SIGNALING MECHANISM.

No. 893,993.

Specification of Letters Patent.

Patented July 21, 1908.

Application filed April 25, 1907. Serial No. 370,171.

To all whom it may concern:

Be it known that I, WILLARD H. GILMAN, of Medford, in the county of Middlesex and State of Massachusetts, have invented certain new and useful Improvements in Signaling Mechanism, of which the following is a specification.

The present invention has reference to signaling mechanism, and more particularly to 10 automatic means for transmitting a predetermined return signal from a distant station to a home or controlling station.

Its principal objects are to provide a simple and effective apparatus of this character 15 which will be non-interfering when several are included in a single line circuit.

In the accompanying drawings, in which similar characters designate like parts throughout the several views,—Figure 1 is a 20 top plan view of one embodiment of the apparatus. Fig. 2 is a front elevation thereof. Fig. 3 is a vertical section on line 2—2 of Fig. 1. Fig. 4 is a perspective view of the detent mechanism and more closely associated parts, 25 and Fig. 5 shows diagrammatically a signaling circuit in which my improved apparatus may be included.

A base 10, preferably of insulating material, is shown as supporting an electro-magnet 30 11 and motor mechanism, the latter being shown as furnished by clock work M, only the more essential parts of which are here illustrated, including a spring 13, a fly 14 frictionally engaging its spindle in the usual 35 manner to permit a certain amount of independent rotation, and an intermediate spindle 15. Secured to the spindle to rotate therewith is a disk 16 provided with a series of peripheral depressions separated by projections 40 17. An unbroken portion of the edge of the disk and these projections maintain coöperation between an upper spring contact member 18 and a lower contact member or anvil 19, but when the depressions pass over the 45 spring it is permitted to leave the anvil.

The rotation of the disk 16 under the influence of the clock work is controlled by an escapement, which may comprise a pair of studs or stop projections 20 21 extending from the front and rear, respectively, of the disk and occupying different angular positions about it, and a coöoperating compound detent N. This detent has a main portion 22 pivoted upon a bracket 23, here shown as secured to 50 the front plate of the clock work, and being

adapted to move horizontally. The portion 22 is provided at the extremity of an angular extension with a cam slot 24 to receive a stud 25 projecting from the armature 26 of magnet 11, said armature being pivoted upon a 60 standard 27 rising from the base. A roll 27^a may be mounted upon the stud to reduce the friction between it and the wall of the slot 24. When released by the magnet, the armature is retracted to swing the detent to the position shown in Fig. 1 by a spring 28 connecting its extension 29 to an adjusting screw 30 rotatable in a post 31. The portion 22 of the detent has pivoted upon it by means of opposite perforated lugs 32 32, a second detent 70 portion 33, independently movable in a plane at right angles to the first. This second portion is bifurcated, it having two arms 34 35 extending upon opposite sides of the edge of the disk 16, and which may be carried by the 75 swing of the main portion 22 beneath the studs 20 and 21, respectively. The portion 33 is also provided with a comparatively long angular arm 36 having a hooked extremity 37 which may engage the fly 14 of the clock 80 work. A spiral spring 38 extending between the detent portions 22 and 33 exerts its tension to tilt the last-named portion back to the position indicated in dotted lines in Fig. 2 when it has been disengaged by the disk 85 studs.

When the armature of the return signal mechanism is in its normal retracted position the hook 37 engages the fly and the stud 20 rests upon the arm 34, the disk occupying 90 the position indicated in Fig. 2 of the drawings, with its unbroken portion holding the spring 18 on the anvil. When the magnet 11 attracts its armature the detent is swung outwardly, carrying the arm 34 from beneath the stud 20 and freeing the disk. This leaves the portion 33 of the detent at liberty to be raised by the action of the spring 38, releasing the fly. The disk is then rotated by the clock work to advance the depressions in its rim over the spring 18 to open and close the circuit of which the contacts 18 and 19 form a part, and thereby transmit a code signal depending for its character upon the relative length of the depressions and 100 projections. After these depressions have passed the spring the stud 21 reaches the arm 35, which now lies in its path, pressing it down and causing the hook 37 to again engage the fly, thereby stopping the clock work. 110

The disk continues to rotate for a short distance or until the outer extremity of the portion 33 reaches its limit of downward movement, when the entire return signal mechanism is brought to a stop. Upon the retraction of the armature by its spring after the deenergization of the electro magnet, the disk is again released and turns through a small angle or until engagement takes place between the stud 20 and the arm 34, the action being similar to that just described. The mechanism is now ready to send another signal.

Attention is called to the fact that upon the arrest of the clock work by the detent for either movement of the armature, the operation is initiated by the conjoint action of the arm 36 and the fly, and the mechanism is thus gradually slowed down until it is brought to a positive stop by the contact of one of the studs with its arm. This diminishes the force with which the studs are pressed against said arms and renders the resultant movement of the detent therefrom easier.

The return signal mechanism also has, in addition to the members 18 and 19, a pair of contacts comprising an upper spring 39 and a spring anvil 40 mounted upon standards 41 rising from the base. As the apparatus is normally positioned, or when the stud 20 rests upon the detent, these contacts are separated by the action of the spring member, but after the disk 16 has completed its signal and the stud 21 engages the detent the contacts 39 and 40 are brought together by a cam projection 42 rotatable with the spindle 15, and there maintained until the detent releases the stud 21 to allow the elements to assume their initial positions, whereupon the cam projection allows the contacts 39 and 40 to open.

The operation of the apparatus may be best considered in connection with the diagram shown in Fig. 5. Here is represented portions of a signaling system, including a home station A provided with a main battery a , a pole changer a' and a neutral relay a^2 for the control of a local sounder circuit, all these elements being connected in the main line L. The line has at least two distant stations B B' each equipped with some suitable mechanism C which is adapted to produce locally a visual or audible signal. This mechanism includes a pair of contacts c , which, for the purposes of this invention may be assumed as closed when the signal is effective and to be capable of control from the home station independently of the other distant stations. The means for securing such selective control need not be here considered, since it forms no part of the present invention. Each station B also has a polarized relay D provided with an armature d and an active contact stop d' and one of my

return signal mechanisms, indicated conventionally at E. The winding of the polarized relay is connected in the line L in series with the contacts 18 and 19 of the apparatus E and has its stop d' joined to the spring 39 by a conductor x . The local circuit of which X is a part, also includes a conductor Y, in which are connected the contacts c , the winding of magnet 11 and a battery f , while a guard conductor z unites the armature of the polarized relay to the contact 40. Suppose now the attendant at the home station has closed the contacts c at the station B and wishes to ascertain that it has been properly done; that is, that the signal is in action at the correct station. By means of the pole changer a' he reverses the connection of the battery a . This transfers the armature of the polarized relays at all distant stations to their stops d' . Now since the contacts c at B are closed, while those at B' are open, because the apparatus C at the latter is not in action, the local circuit xy of the former is completed, energizing the magnet 11 so that the armature 26 is attracted and the detent mechanism operated to release the clock work and disk 16. The depressions in the disk allow the spring 18 to open the line, causing the relay a^2 at the home station to give a corresponding signal, this being indicative of the station B, since each station would be provided with apparatus in which the disk depressions were differently arranged. A reversal of the pole changer will restore the detent to its first position and prepare the mechanism for another answer-back signal. The clock work M must, of course, be wound at suitable intervals.

It may happen that after the home station has closed the contacts c at one distant station and before they have opened again it may become desirable to close the similar contacts at another station. In shifting the pole changer to get the return signal from this second station, the attendant at the home station would again release the mechanism at station B, which was first signaled, by the consequent movement of its polarized relay and a jumble of signals would result. This, however, is prevented by the path maintained for the current through the guard portion z of the circuit xyz by the contacts 39 40 independently of the stop d' , said contacts being held together by the cam projection 42 while contacts c are in their closed or signal actuating position. This complete closure of said circuit, irrespective of the position of the armature of the polarized relay, retains the armature 26 of the return signal mechanism attracted and no answer-back can be sent by any previously operated station mechanism C which is in control of its signals until the return signal circuit has opened in its contacts 39 40. Then

the consequent release of its disk by the detent causes the cam 42 to open the conductor z .

I claim:

- 5 1. A signal transmitting apparatus, comprising a signaling contact device, motor mechanism for operating the contact device, an electro-magnet, a member serving to control the contact device and its motor mechanism and being movable under the attraction of the magnet, and a second contact device included in the circuit of the electromagnet and being operable under the influence of the motor mechanism after the transmission of a signal by the first named contact device and before the production of the succeeding signal.
- 10 2. A signal transmitting apparatus, comprising a contact device, motor mechanism for operating the contact device, and electro-mechanical means for first gradually checking the motor mechanism and therewith positively stopping it.
- 15 3. A signal transmitting apparatus, comprising a contact device, motor mechanism for operating the contact device having members rotatable with it by frictional and positive engagement, and electro-mechanical means successively coöperating with said members.
- 20 4. A signal transmitting apparatus, comprising a contact device, motor mechanism for operating the contact device and having members rotatable with it by frictional and positive engagement, and electro-mechanical means for coöperating first with the frictionally engaged member and finally with the positively engaged member.
- 25 5. The combination with a rotatable contact member, of motor mechanism therefor, stop members rotatable with the contact member and occupying different angular positions with relation thereto, detent mechanism coöperating with the stop members and also with an element of the motor mechanism, and electro-magnetic means for moving the detent mechanism.
- 30 6. The combination with a rotatable con-

tact member, of motor mechanism therefor, stop members rotatable with the contact member and occupying different angular positions with relation thereto, detent mechanism coöperating with the stop members and also with the motor mechanism, and electro-magnetic means for moving the detent mechanism, the portion of the detent mechanism coöperating with the motor mechanism having a releasing and engaging movement different from that portion coöperating with the stop members.

7. The combination with a rotatable contact member, of motor mechanism therefor, stop members rotatable with the contact member, detent mechanism having arms alternately coöperating with the stop members and an arm independently movable in a different plane for coöperation with motor mechanism, and electro-magnetic means for moving the detent mechanism.

8. In a signal transmitting apparatus, the combination with clock work provided with a fly, of a disk rotatable by the clock work and having opposite stop projections, a contact device associated with the disk, detent mechanism provided with arms for alternate engagement with the stop projections and an independent arm for engagement with the fly, and means for actuating the detent mechanism.

9. In a signal transmitting apparatus, the combination with clock work provided with a fly, of a disk rotatable by the clock work and having opposite projections, a contact device associated with the disk, detent mechanism provided with arms for alternate engagement with the projections and an independent arm for engagement with the fly, means for actuating the detent mechanism, a cam member rotatable with the disk, and a contact device operable by the cam member.

In testimony whereof I have affixed my signature, in presence of two witnesses.
